UNITED STATES PATENT OFFICE.

FREDERICK J. RAYFIELD, OF CHICAGO, ILLINOIS.

THERMOSTATIC COOLING SYSTEM FOR INTERNAL-COMBUSTION ENGINES.

1,273,406.

Specification of Letters Patent. Patented July 23, 1918.

Application filed April 18, 1917. Serial No. 163,059.

To all whom it may concern:

Be it known that I, FREDERICK J. RAYFIELD, citizen of the United States, residing at Chicago, in the county of Cook and State 5 of Illinois, have invented certain new and useful Improvements in Thermostatic Cooling Systems for Internal-Combustion Engines; and I do hereby declare the following to be a full, clear, and exact description 10 of the invention, such as will enable others skilled in the art to which it appertains to make and use the same.

This invention relates to improvements in internal combustion engines, and more 15 particularly to means for regenerating the temperature of the cylinders thereof and radiators therefor to the end that the highest motor efficiency may be developed in the shortest possible period following the starting 20 of the motor when cold, and continuously maintained after the motor has become warmed up. This includes obviously the prevention of freezing of the water in the radiators and water jacket of the motor 25 in extremely cold weather, and the saving of fuel and thermal units, and the effecting of an increase in power in proportion to fuel consumption due to the maintenance 30 of the proper temperature of the motor cylinders during operation thereof.

The invention also has for its object to provide thermally controlled means for automatically effecting a switch from a low gravity hydro-carbon to a higher gravity 35 hydro-carbon as soon as the motor shall have attained such a temperature as will adapt it to the consumption of the higher gravity fuel.

Other minor objects of the invention will 40 appear from the following specification.

In the accompanying drawings illustrating suitable embodiments of the invention:

Figure 1— is a side elevation of an internal combustion engine and radiator and 45 cooling system applied thereto, parts of the exhaust manifold being broken away.

Fig. 2— is a sectional view on the line 2—2 of Fig. 1—.

Fig. 3— is a section on the line 3—3 of

50 Fig. 2—.

Fig. 4— is a top plan of a housing for the thermostat and the associated parts.

Fig. 5— is a cross-section on the line 5—5 of Fig. 1—.

Fig. 6— is an elevation of a modified 55 form of an explosion engine and cooling means.

Fig. 13— is a view similar to Fig. 1— showing another embodiment of the 75 invention.

Fig. 14— is a view similar to Fig. 1— partly in section showing the invention embodied in a marine engine.

Similar numerals and letters refer to similar parts throughout the several views. 80

The preferred embodiment of my invention as applied to the engine of a motor-propelled vehicle equipped with a water-cooled motor and radiator is illustrated in the drawings and set forth in this specification, and is not limited to the employment of any particular means for moving the cooling medium through the cooling system. A thermo-siphon system is efficient, but a forced circulation system is preferred. 85 90

The invention comprehends the employment of a circulation system which includes means for automatically causing the cooling liquid to be passed into heat-absorbing relation to means for quickly raising the temperature thereof to the desired point or approximating the same and thereafter causing the same to circulate in whole or in part through the water jackets of the cylinders, the part thereof not circulating through 100 said jackets being deflected through the first named part of the system.

The invention as thus broadly defined may be variously embodied and such em-

bodiments varied to adapt the same to motors of different constructions, arrangements, types and purposes, as will be obvious, the several embodiments shown and described being intended only to illustrate examples of the application to what may be termed standard modern equipments.

In the type of construction illustrated in Fig. —1—, the motor cylinders 1 formed integral with each other in a single casting, are equipped with a water-jacket 2 which is connected with the radiator 39 by means of a pipe 41 leading from the lower end of the radiator to the inlet end of a pump 28 of any suitable type, a pipe 29, valve-housing 19 and pipe 33. The said water-jacket 2 is connected with the upper end of the radiator by means of the pipe or manifold 37.

Water from the lower end of the radiator passes into the valve-housing 19 through the inlet port branch 27 of the latter which connects with the pipe 41. The pipe 33 connects with the outlet passage 14 of the said 25 housings, the latter being also provided with an outlet passage 15 which connects with a pipe 43 through which water is adapted to pass into a pipe or duct adapted to be heated by the hot products of combustion of the motor, and which communicates with the pipe or manifold 37 contiguous to its connection with the upper end of the radiator.

The flow of water through the outlet passages 14 or 15 is controlled by means of a single 35 double-faced valve 17 pivotally mounted within said housing and adapted to seat alternately on the valve-seats 23 and 24 at the mouths of said passages. When the valve 17 is seated on the valve seat 23, the 40 water will circulate through the water jacket 2, and when said valve is seated on the valve-seat 24, the water will circulate through the pipes 43 and 46 and pass in to the radiator, it being obvious that the circulation may be 45 partially both ways when the valve is disposed at any point between the seats 23 and 24.

The shaft 18 carrying the valve 17 is disposed in a small chamber of the housing and 50 in one embodiment or adaptation of the invention projects through a wall of the latter for purposes hereinafter defined.

The said valve 17 is actuated by means of a thermostat A comprising the bellows-diaphragm of well-known construction filled 55 with a volatile liquid having a high coefficient of expansion hermetically sealed therein. The cup or housing 8 of said diaphragm is equipped with a bridge 9 which 60 is anchored to one end of the diaphragm by means of a cylindrical projection 10 which is reciprocably and universally movable with respect to the bridge 9. At its opposite end the diaphragm has fixed thereto a stem 11 65 which is disposed and slidable in the bore

12 of the boss 13 of the housing 8 which is preferably integral with the valve housing 19 which is cast in two parts suitably secured together to provide a water-tight joint. The stem 11 of the diaphragm is hollow and receives a piston 5 mounted at the end of a piston rod 6 projecting from the outer end of the stem and which is reciprocably movable with respect to said stem against the action of the springs 7 and 8 bearing upon 75 opposite ends of the piston and opposite end walls of said stem 11. The valve 17 is connected with the outer end of the piston rod 6 by means of the link 20 and pins 21 and 22. This arrangement enables the diaphragm to expand and contract respectively when the valve is seated on the valve-seats 23 and 24 and obviates undue strains on the said diaphragm.

The housing 8 is suitably mounted on the 85 wall 31 of the water jacket 2 bordering an opening therein in such manner as to provide a water-tight joint, the bridge 9 and a portion of the diaphragm 8 projecting into said water jacket 2 so that the expansion and contraction of the diaphragm will be controlled by the water contained within the said water jacket.

Obviously when the engine is cold on first starting, the diaphragm A will be in collapsed or contracted condition and the valve 17 will be seated on the valve seat 24 instead of on the valve-seat 23, as shown in Fig. —2—, and the path of travel of the cooling liquid will be through passage 16, 95 into and through passage 15, and on through the by-pass pipes 43, 46 and 47, and through the check-valve 25 into and through the radiator 39, pump 28 and pipe 29. The pipe 46 is, in Fig. —1—, shown as passing through 100 the exhaust manifold 45 so that the water is very quickly heated to a temperature for example of one hundred and eighty degrees Fahr. Meanwhile the water in the jacket 2 will be heated to some extent thus expanding 105 the diaphragm A and causing it to exert pressure on the piston 5 through the medium of the spring 7. Movement of the stem 11 to effect this is resisted by the spring-pressed ball 26 engaging in the recess 53 in the stem 11, but as soon as the force of expansion of the diaphragm is sufficient to overcome that 115 resistance the valve 17 will be suddenly moved from seat 24 toward seat 23 or upon the latter.

If the valve 17 is disposed between the limits of its movement the circulation of the liquid will be partly through the jacket 2 and partly through the pipe 46, thus admixing the hotter water in the radiator with 125 the cooler water in the water-jacket, or vice versa. Except in extremely cold weather it is more probable that the water in the radiator will now be hotter than the water in the jacket 2, and when admixed with the latter 130

will increase its temperature and thus effect further rapid expansion of the diaphragm to cause the valve to seat on the valve-seat 23 so that thereafter all water will circulate 5 through the jacket 2.

If the heat radiation in the latter exceeds absorption from the cylinders as might occur when the motor is running very slowly, a drop in temperature will result which will 10 cause the valve 17 to move slightly from the seat 23 and thus effect a circulation of liquid through the pipe 46. The water trapped in the latter will obviously be very much hotter than the water in the jacket 2 15 and radiator 39, and will now become admixed with the latter and raise its temperature to some extent, but if not sufficient to cause the valve 17 to return to seat 23 the continued partial circulation through pipe 20 46 will suffice to supplement heat-absorption from the cylinders to effect raising of the temperature to the point necessary to cause said valve 17 to return to seat 23. Or on the other hand, under certain conditions 25 the valve 17 may remain disposed between both seats as will be obvious.

The compression spring 51 bearing on the ball 50 is adjustable by means of the thumb screw 52 to regulate the force with which 30 ball 49 seats in the recess 53 in stem 11. The lock nut 54 secures the thumb-screw 52 against movement.

Mounted on the shaft 18 of the valve 17, and with which the latter is rigid, is an indicating hand 70 which indicates on a graduated scale on a dial 71 suitably secured to the valve housing 19. This hand will indicate whether the valve is seated on either 35 of the valve seats 23 or 24, or whether it is 40 positioned between said seats.

The said shaft 18 also carries a lever 72 rigid therewith which, as hereinafter described, may be connected with a valve controlling the connection of the carburetor 45 with two sources of supply of hydro-carbon liquids of different specific gravity, such connection being more particularly illustrated in the embodiment shown in Fig. —13—.

In order that when the circulation of 50 the cooling medium is confined entirely to the water jackets of the cylinder and radiator there may be no back-flow through the pipes 47, 46 and 43, and against the valve 17, and thus through the valve casing into 55 the water jackets, I provide a check-valve 60 contiguous to the connection between the said pipe 47 and the conduit 37 which will permit the free flow of liquid into the latter from the pipe 47, but will prevent its 60 turn flow.

The embodiment illustrated in Figs. —1—, —2— and —3— is designed for incorporation in the factory where the automobile is made, and in Fig. —6— I have 65 shown my invention embodied in what

might be termed a retail equipment adapted to be supplied to automobiles already in the hands of the user. In that event there would be no opening through the outer wall of the water jacket through which the 70 bridge 9 of the diaphragm housing could extend. Accordingly, an entirely inclosed housing 58 is provided which is in part integral with the valve housing 9, and is connected by means of the pipes 62 and 66 with 75 the pump and the conduit 37 so as to cause a portion of the water delivered from the pump or entering the inlet end of the same to be passed through the said housing 58. The operation of this embodiment is exactly 80 the same as that shown in Figs. —1—, —2— and —3— so that further description will be unnecessary.

It is desirable, of course, that the diaphragm may be adjusted to some extent 85 with respect to its anchorage in its housing, and in Figs. —7— and —8— I have illustrated means for effecting such an adjustment with a view to more accurately regulating the respective temperatures at 90 which the valve 17 will seat on the valves 23 and 24 respectively. It will be noted that at one end of the diaphragm there is mounted a cylindrical projection provided with an external annular groove of some- 95 what greater width than the thickness of the end wall of the housing. The housing is provided with an opening through which the said projection extends, the peripheral wall of the opening being received in the 100 annular groove in said projection which is reciprocably movable with respect to said end wall. It is further desirable that said projection shall have sufficient freedom of play to accommodate itself to unequal 105 expansions of the diaphragm and, therefore, the fit in the opening is made relatively free. The outer end of said projection is provided with a diametric slot 74 which extends through the end flange thereof, and partly 110 through the cylindrical wall thereof, and receives a plate 75 mounted upon the end of a threaded shank 76 which projects through a cap 77 mounted on a threaded flange 78 projecting from the end wall of 115 the housing concentric with the opening therein, and which effects a water-tight seal for said end of said housing, said threaded shank being adjusted by means of a lock nut 79 in a well-known manner.

It is desirable in at least certain classes of internal combustion engines to employ relatively high gravity hydro-carbon liquids in place of low gravity after the motor is sufficiently hot to effect proper vaporization 120 and carburetion of such heavier liquid, and I contemplate the employment of the thermostatic control hereinbefore described to automatically effect the change of fuel as the motor becomes sufficiently heated to 125 130

efficiently consume the same. Thus two sources of supply of hydro-carbon liquids of different specific gravities may be provided, one of which connects with the pipe 5 80, and the other with the pipe 81, both said pipes leading to a three-way valve housing 82 connected by means of pipe 84 with the carbureter. The stem 85 of the three-way valve is connected by means of a rod 86 10 with the said lever 72 so that when the latter is seated on the valve seat 23, at which time the cylinders will be sufficiently hot to efficiently consume the higher gravity fuel, the latter will be supplied to the carbureter 15 in place of the lower gravity and vice versa.

Referring again to Figs. —1— to —6— inclusive, it will be observed that the pipe 46 when shut off from the circulating system by the seating of the valve on the seat 20 23 will contain water exposed in heat absorbing relation to the hot products of combustion exhausted from the cylinders, and said water will obviously in time become very hot and possibly generate steam. This 25 steam would, of course, be exhausted through the check valve into the radiator, and would merely effect an increase in temperature of all of the liquid in the circulating system. This might, however, in some 30 instances, be objectionable, and, therefore, the embodiment shown in Fig. —13— might be substituted to the extent of a different arrangement of the pipe 46, that is to say, instead of passing the pipe 46 through the 35 exhaust manifold a branch exhaust pipe 87 may be connected with the exhaust manifold opposite the exhaust port of one of the cylinders of the engine. A water jacket 88 may surround a portion of said branch exhaust pipe 87, and interposed in the pipes 40 corresponding to the pipes 43 and 47 of the structure shown in Fig. —1—, so that the water is circulated around said branch pipe 87 when the valve 87 is seated on the valve 45 seat 24. Interposed in the branch exhaust pipe 87 is a butterfly valve 89, the stem 90 of which is connected by means of the rod 91 with the arm 72 on the shaft 18 of said valve 17 so as to effect closure of the pipe 50 87 when the temperature of the cooling liquid has been raised to the desired extent, and the circulation is deflected from the water jacket 88 and through the water jackets 55 of the cylinders.

In Fig. —14— I have shown my invention embodied in a marine type internal combustion motor, wherein the conditions to be met differ materially from those of motor propelled vehicles for use on land. Generally speaking the water jackets of marine engines of this type are connected so as to take water from the body in which the boat is floating, and is passed around the exhaust manifold, and thence through the water

jackets and back into the body of water. 65 This obviously tends to maintain the cylinder temperatures too low, or in the event that the circulation of water is temporarily interrupted, may cause the temperature within the cylinders to rise to too high a 70 point. My invention is adapted to overcome these difficulties, but the embodiment differs as aforesaid to the extent necessary to obtain the desired results.

In this embodiment the pump 92 is connected at its inlet end by means of the pipe 93 with the body of water in which the boat is floating. The outlet end of the pump is connected by means of the pipe 93 with the valve casing 19 constructed the same as that 75 shown in Figs. —2— and —3—. One side of the valve casing is connected by means of a pipe 94 with a water jacket 95 surrounding the exhaust manifold 96, and from the said water jacket 95 a pipe 97 leads to a 80 valve housing 98 similar to the valve housing 19 and provided with an oscillating valve 99 adapted to seat on either of two valve seats. One of the latter is at the mouth of an exhaust pipe 100 through 85 which water is discharged back into the body from which it is received, and the other, 101, connects with the water jackets through a check-valve casing 102. The said 90 check valve casing is provided with two check valves 103 and 104 respectively, the former permitting free flow from the pipe 101 into the water jackets, and the valve 104 preventing flow through the pipe 105. The latter is connected with the other side 95 of the valve housing 19, and is adapted to cause water to pass from said valve housing directly through the check valve casing 102 past the check valve 104 into the water jacket. As it is desirable in this class of 100 motors that the exhaust manifold be maintained cool, it is inadvisable to entirely shut off the circulation of water through the water jacket 95, and for this purpose a 105 bypass pipe 106 is provided which connects 110 the pipe 93 with the pipe 94 and is provided with a valve 107 which may be adjusted to regulate the volume of flow past the valve housing 19 when the valve is seated to cut off flow through the pipe 94.

The diaphragm housing 108 is connected by means of a pipe 109 with the pump 92 and by means of a pipe 110 with the water jacket.

Marine engines are not required to meet 120 the same conditions of service as engines of motor propelled vehicles on land for the reason that they are under a far more constant load for a longer period, and are water-cooled instead of air-cooled. Hence, 125 the only object to be accomplished by this invention is to prevent the marine engine from being maintained too cool by a too

steady flow of water through the water jackets thereof, but to maintain the temperature of the engine very uniform.

The operation of the invention when applied to marine motors is, owing to the unlimited supply of water for cooling purposes, somewhat different from that of the land engine. It will be seen that in starting the motor the valve 18 will be positioned to cause the water to pass first to the water jacket 95, and thence through the water jackets of the cylinders, and thereafter back into the body of water from which it is received. The water is primarily heated by the exhaust pipe, and its temperature further increased by absorption of heat from the cylinders. As the heat of the engine increases the circulation of water passing through the water jackets is cut off from the water jacket 95 around the exhaust pipe, and only a small quantity enters the latter from the by-pass pipe around the valve-casing 19.

As previously stated the invention may be variously embodied to adapt it to engines for various purposes and used under varying conditions, but all such modifications in construction as may be necessary to adapt the invention to such various purposes are comprehended within the scope of the invention as defined in the appended claims.

I claim as my invention:

1. In a cooling system for internal combustion engines equipped with water-jackets, a source of supply of a cooling liquid, means other than the water-jacket of the cylinders for heating the said liquid, means for effecting circulation of the liquid through the water-jacket, and in heat absorbing relation to said heating means, and thermally controlled means for shutting off the circulation of liquid through one or the other of said means or effecting circulation thereof partly through both in accordance with variations in temperature of said liquid.

2. A cooling system for internal combustion engines including water-jackets for the engine cylinders, a water conduit associated with the exhaust manifold for heating water by means of the hot products of combustion, a source of supply of a liquid adapted to circulate through said jackets and said conduit, and thermally controlled means for causing the water to circulate either through said conduit or said jackets or simultaneously through both.

3. A cooling system for internal combustion engines including water-jackets for the engine cylinders, a water conduit associated with the exhaust manifold for heating water by means of the hot products of combustion, a source of supply of a liquid

adapted to circulate through said jackets and said conduit, and means controlled by the temperature of the liquid contained in said jackets for causing the water to circulate either through said conduit or said jackets or simultaneously through both. 70

4. In a cooling system for internal combustion engines, a source of supply of a cooling medium, means for effecting circulation thereof in contact with the cylinders for absorbing heat from the latter, a conduit for said liquid disposed to heat the latter by the products of combustion exhausted from the cylinders, a valve for controlling the circulation of said liquid to confine the same to either of the said two sources of heat, and thermally actuated means for automatically operating said valve. 80

5. In a cooling system for internal combustion engines, a source of supply of a cooling medium, means for effecting circulation thereof in contact with the cylinders for absorbing heat from the latter, a conduit for said liquid disposed to heat the latter by the products of combustion exhausted from the cylinders, a valve for controlling the circulation of said liquid to confine the same to either of the said two sources of heat, and means actuated by variations in temperature of the liquid for automatically operating said valve. 90

6. A cooling system for internal combustion engines including water-jackets for the engine cylinders, a water conduit associated with the exhaust manifold for heating water by means of the hot products of combustion, a radiator connected with said jackets and conduit for normally causing the cooling liquid to circulate through said parts, and a valve controlled by the variations in temperature of the liquid for cutting off circulation through the jackets or the conduit or partially from each. 100

7. A cooling system for internal combustion engines including the water jackets of the cylinders and a conduit disposed in heat absorbing relation to the exhaust gases from said cylinders, a source of supply of liquid, a single thermostatically actuated valve controlling the circulation of said liquid for causing the same to pass through either or partly through both the jackets and conduits, and means associated with said valve for resisting movement thereof in one direction. 110

8. A cooling system for internal combustion engines including the water jackets of the cylinders and a conduit disposed in heat absorbing relation to the exhaust gases from said cylinders, a source of supply of liquid, a single thermostatically actuated valve controlling the circulation of said liquid for causing the same to pass through either or 115

partly through both the jackets and conduits, and means associated with said valve for resisting movement thereof in one direction while permitting free movement there- 5 of in the opposite direction.

9. A cooling system for internal combustion engines including the water jackets of the cylinders and a conduit disposed in heat absorbing relation to the exhaust gases 10 from said cylinders, a radiator, a single thermostatically actuated valve controlling the circulation of said liquid for causing the same to pass from the radiator through either or partly through both the jackets 15 and conduits back to the radiator, and cushioning means associated with said valve and said thermostatic actuating means therefor for yieldingly holding the said valve at the respective limits of its move- 20 ment.

10. A cooling system for internal combustion engines including the water jackets of the cylinders and a conduit disposed in heat-absorbing relation to the exhaust gases 25 from said cylinders, a radiator, a valve controlling the circulation of said liquid for causing the same to pass from the radiator through either or partly through both the jackets and conduits and back to the radiator, thermostatically responsive means 30 connected with said valve for actuating the same, and cushioning means interposed in said connection.

11. In a cooling system for water-jacketed 35 engines, a water conduit disposed in heat absorbing relation to the products of combustion exhausted from the engine, a radiator, means for effecting forced passage of water from the said radiator to the said 40 conduit and the water jacket of the engine, return connection from the latter to said radiator, a valve for causing a flow from one of said water-heating parts to the exclusion of the other, and a temperature re- 45 sponsive element associated with said valve for actuating the same.

12. In a cooling system for water-jacketed engines, a water conduit disposed in heat absorbing relation to the products of combustion exhausted from the engine, a radiator, means for effecting forced passage of water from the said radiator to the said 50 conduit and the water jacket of the engine, return connection from the latter to said radiator, a valve for causing a flow through one of said water-heating parts to the exclusion of the other, and a temperature responsive element disposed in heat-absorbing relation only to the water contained in or 55 flowing through the water jacket and operatively connected with said valve for actuating the same.

13. In a cooling system for water-jacketed engines, a water conduit disposed in heat-

absorbing relation to the products of combustion exhausted from the engine, a source of supply of water, means for effecting forced passage of water from the said source to the said conduit and the water jacket of the engine, return connection from the latter to said source, a valve for causing a flow through one of said water-heating parts to the exclusion of the other, a temperature responsive element disposed in heat-absorbing relation to the water flowing through the water jacket and operatively connected with said valve for actuating the same, and means associated with said connection for effecting a sudden movement of said valve from one position there- 65 of to another.

14. In a cooling system for water-jacketed engines, a water conduit disposed in heat-absorbing relation to the products of combustion exhausted from the engine, a source of supply of water, means for effecting forced passage of water from the said source to the said conduit and the water jacket of the engine, return connection from the latter to said source, a valve for causing a flow through a temperature responsive element disposed in heat-absorbing relation to the water flowing through the water jacket and operatively connected with said valve for actuating the same, and means associated with said connection for effecting a sudden movement of said valve from one position there- 70 of to another, 75 said means including means for permitting a slow movement of the valve in all directions of 80 its movement through a part of the latter after having attained its last-mentioned position.

15. In a cooling system for water-jacketed engines, a water conduit disposed in heat-absorbing relation to the products of combustion exhausted from the engine, a source of supply of water, means for effecting forced passage of water from the said source to the said conduit and the water jacket 105 of the engine, return connection from the latter to said source, a valve for causing a flow through one of said water-heating parts to the exclusion of the other, a temperature responsive element disposed in heat-absorbing relation to the water flowing through the water jacket and operatively connected with said valve for actuating the same, two sources of supply of hydro-carbon of different specific gravities for said engine, and 110 operative connection between the same and said temperature responsive element for automatically connecting the latter with the source of higher gravity hydro-carbon as the engine temperature becomes sufficiently high 115 to efficiently consume the same.

16. In an internal combustion engine having water jacketed cylinders constituting

- means for heating water as the cylinders become hot and having connection with sources of supply of two hydro-carbons of different specific gravities, a valve adapted 5 to cut off one of said sources of supply as the other is cut in, and a heat responsive element disposed in heat-absorbing relation to the water heated by said cylinders and operatively connected with said valve to 10 actuate the same.
17. A cooling system for internal combustion engines including the water jackets of the cylinders and a conduit disposed in heat-absorbing relation to the exhaust gases from 15 said cylinders, a radiator, a valve controlling the circulation of said liquid for causing the same to pass from the radiator through either or partly through both the jackets and conduits and back to the radiator, 20 thermostatically responsive means connected with said valve for actuating the same, and a check-valve interposed in the discharge end of the said conduit for preventing back-flow from the radiator into the 25 same.
18. A cooling system for internal combustion engines including the water jackets of the cylinders and a conduit disposed in heat-absorbing relation to the exhaust gases from 30 said cylinders, a radiator, a valve controlling the circulation of said liquid for causing the same to pass from the radiator through either or partly through both the
- jackets and conduits and back to the radiator, thermostatically responsive means connected with said valve for actuating the same, and a check-valve interposed in the discharge end of said conduit for preventing back-flow from the radiator into the same when circulation through said conduit 35 is cut off by said temperature responsive means. 40
19. A cooling system for internal combustion engines including the water jackets of the cylinders and a conduit disposed in heat-absorbing relation to the exhaust gases from 45 said cylinders, a radiator, a valve controlling the circulation of said liquid for causing the same to pass from the radiator through either or partly through both the jackets and conduits and back to the radiator, thermostatically responsive means connected with said valve for actuating the same, and means disposed at the discharge 50 end of said conduit for preventing back-flow 55 of water from the radiator into the same as the circulation through said conduit is cut off by said temperature responsive element.

In testimony whereof I have signed my name in presence of two subscribing witnesses. 60
